UNITED STATES PATENT OFFICE.

AUGUSTE CAMILLE EDMOND RATEAU, OF PARIS, FRANCE, ASSIGNOR TO
RATEAU STEAM REGENERATOR COMPANY, OF CHICAGO, ILLINOIS, A
CORPORATION OF WEST VIRGINIA.

REGULATING APPARATUS FOR ENGINES.

No. 839,318.

Specification of Letters Patent.

Patented Dec. 25, 1906.

Application filed December 31, 1904. Serial No. 239,186.

To all whom it may concern:

Be it known that I, AUGUSTE CAMILLE EDMOND RATEAU, a citizen of France, residing at Paris, France, have invented a certain new and useful Improvement in Regulating Apparatus for Engines, of which the following is a full, clear, concise, and exact description, reference being had to the accompanying drawings, forming a part of this specification.

My invention relates to motors employing fluids preferably supplied to the engine or motors at different points and preferably, though not necessarily, at different pressures derived from different sources. One source may be regenerated exhaust-steam. The other source may be a source of steam of higher pressure, as the boiler-steam, which I employ to supplement the lower-pressure steam in order that the deficiency thereof, which may vary, may be supplied.

My invention has been employed in connection with steam-turbines, though it is not to be limited to this use, and in practicing my invention I employ valves one regulating the application of the low-pressure steam to the engine and the other the application of the high-pressure steam, in conjunction with which valves I employ a valve-regulating apparatus whereby more or less of steam from each source may be admitted to the engine.

My invention has as an important object the control of the valves governing the admission of high and low pressure operating fluid or steam through the agency of operating steam or fluid, and the invention has been found of particular service in that class of power-producing mechanism where steam is admitted from the low-pressure source to the low-pressure motor or engine element and wherein steam is admitted from the high-pressure source to the high-pressure element of the motor or engine.

I have very successfully employed the apparatus of my invention in connection with steam regenerative accumulators or regenerators—such, for example, as are set forth in my Patent No. 679,242, dated April 12, 1901. I have employed a valve-regulating means having common influence upon the valves controlling the admission of the high and low pressure steam, which valve-regulating means has been arranged to be within the influence of the low-pressure steam admitted from the

steam-accumulator, whereby proper regulation of the low and high pressure valves may be effected to regulate the requisite application of steam to the engine, so that all possible steam of the low-pressure source will be utilized in the turbine or engine and the high-pressure steam is called upon only to supply a deficiency in the low-pressure steam. I do not wish to be limited, however, to the source of steam that is employed for controlling the valve-regulating means.

By means of my invention it is not necessary to have two sources that supply steam in steady fluxes. I have preferably employed two distinct engine elements, to one of which the low-pressure operating steam or fluid is admitted and to the other of which the high-pressure steam is admitted; but I do not wish to be limited to the precise way in which the low-pressure and the high-pressure steam are admitted to the composite engine or engine adapted for double pressures that I have practiced.

In the preferred embodiment of my invention there has been employed a piston-rod or plunger attached to piston mechanism, which piston mechanism is preferably constantly under the influence of the low-pressure steam and of spring mechanism, the spring mechanism acting upon the piston mechanism in one direction, while the low-pressure steam acts upon said piston mechanism in the opposite direction, these opposing forces when operating normally serving to maintain the piston mechanism in a given position, whereby the valves may be subject to the control of a speed regulator or governor to maintain the proper speed of the engine. By means of my invention this same governing agency is also permitted to have the proper control of the speed irrespective of the positions the piston mechanism may assume through the influence of the low-pressure steam and the spring mechanism acting thereupon.

The governing mechanism preferably secures for each change in its condition of operation a similar change in the adjustment of the valves, while the valve-regulating mechanism that is controlled by the steam preferably effects a differential or unlike adjustment of the valves.

I will explain my invention more fully by reference to the accompanying drawings,

showing one application and embodiment of the invention, in which—

Figure 1 is a view somewhat structural and somewhat diagrammatic, illustrating the application of my invention to a steam engine or turbine whose energy is supplied from a steam accumulator or regenerator and also from a source of higher pressure, as the boiler, from which the steam-accumulator 10 indirectly receives its steam, which has previously been used, for example, in an engine. Fig. 2 is a plan view of a portion of the apparatus illustrated in Fig. 1, excepting that the ball-governor is swung at right angles to the 15 position shown in Fig. 1. Fig. 3 is a detail view showing one of many types of valve structures that may be employed in controlling the admission of steam into the steam-engine or turbine. Fig. 4 is a view somewhat diagrammatic, illustrating a modification of the apparatus shown in Figs. 1 and 2.

Like parts are indicated by similar characters of reference throughout the different figures.

25 The invention, having been shown in connection with a steam regenerator or accumulator, I have diagrammatically indicated various elements that enter into such system. The initial source of steam-pressure is the 30 boiler *a*, that furnishes live steam to an engine *b*, that may be employed for performing any suitable work and which use is immaterial in connection with my present invention, the exhaust of which engine is received in a 35 steam regenerative accumulator *c*, such as has been illustrated, for example, in my aforesaid patent. The steam from the steam-regenerators, such as *c*, is frequently used in the operation of steam-engines as 40 turbines, to which end there is employed a valve mechanism—such, for example, as that indicated in Fig. 3—that controls the entry of the steam from the steam-accumulator to the low-pressure element *d* of the steam engine or turbine. A valve mechanism 45 *e*, preferably similar to the valve mechanism shown in Fig. 3, is employed for controlling the admission of steam which is at a higher pressure than that supplied from the 50 accumulator *c*, which steam at such increased pressure may, for example, be received from the boiler *a*, this steam at increased pressure being thus live steam, though I do not wish to be limited to the particular source from 55 which the steam at high pressure is received.

As a description of one of the valve structures will answer as a description of both, the structure illustrated fully in Fig. 3 will only be specifically explained. The casing *f* defines a steam-chamber, from the upper part of which a bell-shaped element *g* is depended, which bell-shaped element is provided with a series of ports *h*, that communicate with the space about said element *g*, in which 65 space the steam from the source of supply is

received. Within the bell-shaped element there is provided a reciprocating valve element *i*, that has a vertical flange portion *k*, that serves when in a depressed position to seal the ports *h*. When this valve element *i* is in an elevated position, the flange or piston portion *k* is uncovered from the ports *h*, whereby steam may find passage into the channel *m*. Openings *l* are provided in the plunger or piston *k*, so that the steam admitted through the ports *i* may surround said piston and balance the same.

There may be any suitable form of connection established between the low and high pressure controlling steam-valves. I have indicated a pipe *n*, conveying low-pressure steam to the low-pressure motor element, and a pipe *o* for bringing high-pressure steam to the high-pressure motor element. The valve-stems *p* and *q* of the low and high 85 pressure valves are articulated to the links *r* and *s*, respectively, which links are fixed upon shafts, to which are also fixed links *r'* and *s'*, which latter links are flexibly connected with links *r''* and *s''*, that are pivoted 90 or linked together at their adjacent ends. It will be seen that the stems *p* *q* work in stationary guides that are shown at their lower ends. A connecting-rod *t* is also linked to the links *r''* and *s''* where the latter are 95 joined. The bell-crank lever *t'*, having a fixed axis of rotation at its elbow, has one of its arms linked to the connecting-rod *t* and the other of its arms in engagement with a collar *t''*, that forms a part of a well-known 100 ball-governor *t''*, and which is diagrammatically indicated in connection with the engine or turbine. It will be apparent that this ball-governor and the link mechanism that I have described in connection with it serve to 105 rock the arms *r* and *s* as the speed of the engine changes, so that the valves controlling the low and high pressure steam will be simultaneously controlled to maintain the 110 speed of the engine.

The governing mechanism that has thus been particularly described is supplemented by a pressure-governor which is desirably regulated by the low-pressure steam. This pressure-governor in Fig. 1 is illustrated in 115 the form of a cylinder *u*, to the bottom of which is led a steam-passage *u'*, that leads preferably directly from the pipe immediately leading from the steam-accumulator, so as directly to be subject to the low-pressure steam. Within this cylinder there is located a piston *u''*, interposed between which and the cap *u'''* of the cylinder is a coil-spring *u'''*. The low-pressure steam is admitted below the piston and in conjunction 120 with the spring above serves to define the position of the piston within the cylinder. The piston is provided with a piston-rod *u''''*, that may be pivoted thereto somewhat in the manner of the piston and rod construction of 130

While I prefer to admit the operating steam or fluid at different points to the engine, I do not wish to be limited in all embodiments of my invention to this characteristic, as the valve regulation is an important feature of the invention, irrespective of the mode of application of the operating fluid or steam to the engine or turbine.

Obviously the engine *b* may be closed down for periods of time, the supply of steam to the accumulator ceasing between the intermittent operations of the engine, in which case the added engine or turbine may be operated solely from the boiler-supply. The flow of steam from the accumulator may thus vary or cease, an automatic regulation of the supply of steam from the boiler maintaining the proper supply of steam to the turbine to enable the turbine properly to perform its work.

As indicated in this description and in the drawings, the engine or turbine has two operating elements, these operating elements acting upon a common load, a shaft being indicated as the common connection between the two operating elements of the engine, wherefore each operating element of the engine may in itself be a complete engine structure, but forming a component part of the aggregate engine or prime mover, by reason of the common connection between the two.

I use the term "high pressure" and "low pressure" herein in their relative sense, meaning that one pressure is higher than the other.

In my division of this application, Serial No. 277,710, filed September 9, 1905, I have broadly claimed the system employing the accumulator herein disclosed and specifically claim the apparatus shown in Fig. 4.

It will be seen that I have produced an apparatus that works to particular advantage in connection with operating fluid of different pressures supplied to the engine or turbine construction at such different pressures; but I do not wish to be limited to the application of fluid at different pressures.

It is obvious that many changes may be made in the apparatus of my invention without departing from the spirit thereof, and I do not therefore wish to be limited to the precise embodiments of my invention; but,

Having thus described my invention, I claim as new and desire to secure by Letters Patent—

1. The combination with an engine adapted to be operated by fluids of differing pressures, of a source of low-pressure fluid, a source of higher-pressure fluid, valves controlling the passage of fluid from said sources to said engine, and piston mechanism effecting control of said valves and governed by operating fluid, substantially as described.

2. The combination with an engine adapt-

ed to be operated by fluids of differing pressures, of a source of low-pressure fluid, a source of higher-pressure fluid, valves controlling the passage of fluid from said sources to said engine, piston mechanism effecting control of said valves, a connection effecting the application of the low-pressure fluid to said piston mechanism, and spring mechanism opposing the action of said low-pressure fluid upon the piston, substantially as described.

3. The combination with an engine adapted to be operated by fluids of different pressures, of a source of low-pressure fluid, a source of higher-pressure fluid, valves controlling the passage of fluid from said sources to said engine, piston mechanism effecting control of said valves, a connection leading fluid from one of said sources of supply to said piston mechanism, and spring mechanism opposing the action of said low-pressure fluid upon the piston, substantially as described.

4. The combination with an engine adapted to be operated by fluids of differing pressures, of a source of low-pressure fluid, a source of higher-pressure fluid, valves controlling the passage of fluid from said sources to said engine, a piston having operative connection with both of said valves, a cylinder therefor, a spring operating in one direction upon said piston, and a connection whereby fluid may operate upon said piston in the other direction, substantially as described.

5. The combination with an engine adapted to be operated by fluids of differing pressures, of a source of low-pressure fluid, a source of higher-pressure fluid, valves controlling the passage of fluid from said sources to said engine, a piston having operative connection with both of said valves, a cylinder therefor, a spring operating in one direction upon said piston, and a connection between the low-pressure source of fluid for having said fluid act upon one side of the piston, substantially as described.

6. The combination with an engine adapted to be operated by fluids of differing pressures, of a source of low-pressure fluid, a source of higher-pressure fluid, valves controlling the passage of fluid from said sources to said engine, and valve-controlling mechanism governing said valves operated by fluid received from one of said sources, substantially as described.

7. The combination with an engine adapted to be operated by fluids of differing pressures, of a source of low-pressure fluid, a source of higher-pressure fluid, valves controlling the passage of fluid from said sources to said engine, piston mechanism effecting control of said valves, a connection effecting the application of the low-pressure fluid to said piston mechanism, and an agency opposing the action of said low-pressure fluid upon the piston, substantially as described.

the Brotherhood engine. The other end of this piston-rod u^5 is shown connected with the elements r^1 , s^2 , and t where these elements are joined, all of which elements, together with the element u^5 , thus have a common axis of rotation. Where the pressure from the low-pressure source of steam becomes excessive, the piston u^2 will rise against the force of the spring u^4 , whereby the link r^1 will be moved in a counter-clockwise direction and the link s^2 will be moved in a clockwise direction, whereby the links r and s are respectively moved in counter-clockwise and clockwise directions, whereby the low-pressure valve permits the flow of more low-pressure steam and the high-pressure valve permits the flow of less high-pressure steam. When, however, the low-pressure steam decreases in pressure, the spring u^4 effects depression of the piston u^2 , causing a clockwise movement of the arm r^1 and the link r and a counter-clockwise movement of the arm s^2 and the link s , thereby reducing the flow of low-pressure steam and increasing the flow of high-pressure steam, whereby the said engine may have the requisite amount of energy applied thereto to secure its effective operation.

I have immediately above described some specific positions or conditions of the throttles or inlet-valves for the high and low pressure steam. It is obvious that under certain circumstances the low-pressure valve may be altogether closed and the high-pressure valve opened and under other circumstances that the high-pressure valve may be altogether closed and the low-pressure valve opened. It will thus be seen that I have provided automatically-operated throttles, which in association with the speed-governor will enable the engine to take care of varying loads at requisite speed. It will also be seen that I have provided an improved power-generating system including two sources of operating fluid, an engine adapted to be operated by fluid received from these sources, valves controlling the passage of said fluid from said engine, mechanism controlled by operating fluid (preferably received from the low-pressure source) for effecting opening action upon one valve as it has closing action upon the other valve, whereby the relative positions of said valves are determined, and a speed-governor simultaneously exerting opening or closing action upon said valves, whose relative positions are thus determined. In the specific embodiment of the invention which I have practised the engine will be operated by fluid received from the source c altogether as long as there is sufficient fluid receivable from said source; but when the fluid supplied from the source c is deficient the quantity required will be made up from the source a , supplied through the pipe o .

In Fig. 4 I have illustrated one of many

other forms of my invention. In this construction I have employed two dash-pots instead of one, as shown in Fig. 1, the pistons v whereof are shown attached to the pipe w and within cases x x' , which are provided with link connections y y' , which control, respectively, the low and high pressure valves. The pipe w has attached thereto a flexible duct z , communicating with the source of low-pressure steam. The pipe w is connected with a connecting-rod t , which is provided for the same purpose as the connecting-rod t in the arrangement shown in Fig. 1. The pipe w serves to admit steam between the pistons v and their casings, springs being upon the other side of the said pistons. A reciprocation of the pipe w will cause movement of the links y y' for purposes of speed regulation. Motion of the links y y' independent of the pipe w is effected upon variation in the pressure of the steam behind the pistons, as has been explained and will be understood.

I am of course aware of compound engines and the admission of exhaust-steam from the high-pressure cylinders thereof to their low-pressure cylinders; but in such apparatus the source of steam from which the low-pressure cylinder is supplied is a component part of the engine.

In the apparatus of my present invention the two sources of steam are distinct from the engine, though the source of low-pressure steam is indirectly supplied in some embodiments of the invention from the source of high-pressure or boiler steam. These sources of steam, however, so far as they are related to the engine, are distinct from the engine.

It will be seen that I have provided a very important advance in the art of power generation, which in its preferred embodiment resides in a source of high-pressure steam employed to operate an engine directly, a source of low-pressure steam which is supplied by and replenished by the exhaust of said engine, and a second engine, preferably a turbine, receiving steam from the source of low-pressure steam and receiving steam from the source of high-pressure steam, the boiler, the said high-pressure and low-pressure sources of steam being, as stated, independent with respect to that engine which they both supply. This latter engine is most desirably a steam-turbine, as it best utilizes the steam from the low-pressure source.

While I prefer to supply the steam-turbine or other similarly-placed engine with steam from the same boiler that supplies the main engine that exhausts into the accumulator or regenerator, I do not wish to be limited to this same boiler for supplying the high-pressure steam to the turbine. I therefore in the claims use the term "boiler-pressure" in the broadest sense.

8. The combination with an engine adapted to be operated by fluids of differing pressures, of a source of low-pressure fluid, a source of higher-pressure fluid, valves controlling the passage of fluid from said sources to said engine, piston mechanism effecting control of said valves, a connection leading fluid from one of said sources of supply to said piston mechanism, and an agency opposing the action of said low-pressure fluid upon the piston, substantially as described.

9. The combination with an engine adapted to be operated by fluids of differing pressures, of a source of low-pressure fluid, a source of higher-pressure fluid, valves controlling the passage of fluid from said sources to said engine, a piston having operative connection with both of said valves, a cylinder therefor, an agency operating in one direction upon said piston, and a connection whereby fluid may operate upon said piston in the other direction, substantially as described.

10. The combination with an engine adapted to be operated by fluids of differing pressures, of a source of low-pressure fluid, a source of higher-pressure fluid, valves controlling the passage of fluid from said sources to said engine, a piston having operative connection with both of said valves, a cylinder therefor, an agency operating in one direction upon said piston, and a connection between the low-pressure source of fluid for having said fluid act upon one side of the piston, substantially as described.

11. The combination with an engine adapted to be operated by fluids of differing pressures, of a source of low-pressure fluid, a source of higher-pressure fluid, valves controlling the passage of fluid from said sources to said engine, and valve-controlling mechanism governing said valves operated by fluid received from the low-pressure source, substantially as described.

12. The combination with an engine adapted to be operated by fluids of differing pressures, of a source of low-pressure fluid, a source of higher-pressure fluid, a valve controlling the passage of low-pressure fluid to said engine, and valve-controlling mechanism governing said valve and operated by fluid received from one of said sources, substantially as described.

13. The combination with an engine adapted to be operated by fluids of differing pressures, of a source of low-pressure fluid, a source of higher-pressure fluid, a valve controlling the passage of low-pressure fluid to said engine, and valve-controlling mechanism governing said valve and operated by fluid received from the low-pressure source, substantially as described.

14. The combination with an engine adapted to be operated by fluids of differing pressures, of a source of low-pressure fluid, a source of higher-pressure fluid, the piping

that supplies the low-pressure fluid extending to the low-pressure portion only of said engine, a valve controlling the passage of low-pressure fluid to said engine, and valve-controlling mechanism governing said valve and operated by fluid received from one of said sources, substantially as described.

15. The combination with an engine adapted to be operated by fluids of differing pressures, of a source of low-pressure fluid, a source of higher-pressure fluid, the piping that supplies the low-pressure fluid extending to the low-pressure portion only of said engine, a valve controlling the passage of low-pressure fluid to said engine, and valve-controlling mechanism governing said valve and operated by fluid received from the low-pressure source, substantially as described.

16. The combination with an engine adapted to be operated by fluids of differing pressures, of a source of low-pressure fluid, a source of higher-pressure fluid, the piping that supplies the high-pressure fluid extending to the high-pressure portion only of said engine, a valve controlling the passage of low-pressure fluid to said engine, and valve-controlling mechanism governing said valve and operated by fluid received from one of said sources, substantially as described.

17. The combination with an engine adapted to be operated by fluids of differing pressures, of a source of low-pressure fluid, a source of higher-pressure fluid, the piping that supplies the high-pressure fluid extending to the high-pressure portion only of said engine, a valve controlling the passage of low-pressure fluid to said engine, and valve-controlling mechanism governing said valve and operated by fluid received from the low-pressure source, substantially as described.

18. The combination with an engine adapted to be operated by fluids of differing pressures, of a source of low-pressure fluid, a source of higher-pressure fluid, valves controlling the passage of fluid from said sources to said engine, and a speed-governor for regulating the operation of both of said valves.

19. The combination with an engine adapted to be operated by fluids of differing pressures, of a source of low-pressure fluid, a source of higher-pressure fluid, valves controlling the passage of fluid from said sources to said engine, a speed-governor for regulating the operation of both of said valves, and additional valve-controlling mechanism operated by steam from one of said sources.

20. The combination with an engine adapted to be operated by fluids of differing pressures, of a source of low-pressure fluid, a source of higher-pressure fluid, valves controlling the passage of fluid from said sources to said engine, a speed-governor for regulating the operation of both of said valves, and additional valve-controlling mechanism operated by steam from the low-pressure source.

21. The combination with an engine adapted to be operated by fluids of differing pressures, of a source of low-pressure fluid, a source of higher-pressure fluid, valves controlling the passage of fluid from said sources to said engine, a speed-governor for regulating the operation of both of said valves, and additional valve-controlling mechanism acting upon said valves operated by steam from one of said sources.
22. The combination with an engine adapted to be operated by fluids of differing pressures, of a source of low-pressure fluid, a source of higher-pressure fluid, valves controlling the passage of fluid from said sources to said engine, a speed-governor for regulating the operation of both of said valves, and additional valve-controlling mechanism acting upon said valves operated by steam from the low-pressure source.
23. A power-generating system including two sources of fluid, an engine adapted to be operated by fluid received from said sources, valves controlling the passage of fluid from said sources to said engine, and valve-controlling mechanism governing said valves and actuated by operating fluid, substantially as described.
24. A power-generating system including two sources of fluid, an engine adapted to be operated by fluid received from said sources, valves controlling the passage of fluid from said sources to said engine, and valve-controlling mechanism governing said valves and actuated by the operating fluid received from one of said sources, substantially as described.
25. A power-generating system including two sources of fluid, an engine adapted to be operated by fluid received from said sources, valves controlling the passage of fluid from said sources to said engine, and speed-governing mechanism acting upon both of said valves, substantially as described.
26. A power-generating system including two sources of fluid, an engine adapted to be operated by fluid received from said sources, valves controlling the passage of fluid from said sources to said engine, speed-governing mechanism operating upon said valves, and

valve-controlling mechanism governing said valves and actuated by the operating fluid received from one of said sources, substantially as described.

27. A power-generating system including two sources of fluid, an engine adapted to be operated by fluid received from said sources, valves controlling the passage of fluid from said sources to said engine, and valve-controlling mechanism governing said valves and actuated by operating fluid and serving to have opening action upon one valve while having closing action upon the other valve, substantially as described.

28. A power-generating system including two sources of fluid, an engine adapted to be operated by fluid received from said sources, valves controlling the passage of fluid from said sources to said engine, and valve-controlling mechanism governing said valves and actuated by the operating fluid received from one of said sources and serving to have opening action upon one valve while having closing action upon the other valve, substantially as described.

29. A power-generating system including two sources of fluid, an engine adapted to be operated by fluid received from said sources, valves controlling the passage of fluid from said sources to said engine, valve-controlling mechanism governing said valves and actuated by the operating fluid received from one of said sources and serving to have opening action upon one valve while having closing action upon the other valve, and speed-governing mechanism also operating upon said valves, substantially as described.

30. A power-generating system including an engine, two fluid-ducts conveying operating fluid therefor, a valve in one duct operated by fluid conveyed by the other duct, and a speed-governor operating upon said valve, substantially as described.

In witness whereof I hereunto subscribe my name this 27th day of October, A. D. 95 1904.
